UNITED STATES PATENT OFFICE.

JULIEN A. BRIED, OF OAKLAND, CALIFORNIA.

POWER CLOTHES WRINGER.

Application filed September 21, 1920. Serial No. 411,838.

To all whom it may concern:

Be it known that I, JULIEN A. BRIED, a citizen of the United States, residing at Oakland, in the county of Alameda and State of California, have invented a new and useful Improvement in a Power Clothes Wringer, of which the following is a specification and which is illustrated in the accompanying drawings.

10 My invention relates to power driven clothes wringers as used with modern household power driven washing machines, and has for its object the more convenient arrangement of such wringers in relation to existing stationary wash tubs as found in the laundries of private homes, and in relation to the washing machine proper.

15 Fig. 1 is a perspective drawing showing the general arrangement of my wringer and gearing in position over a pair of stationary tubs.

Fig. 2 shows in larger scale, a side view of a portion of the wringer with its shaft released from the gearing.

20 Fig. 3 shows in a larger scale, a center cross section of the power shaft connections between the gear boxes.

Fig. 4 shows a universal power connection to a washing machine. Fig. 5 shows 25 in horizontal cross section a modified power delivery gear arrangement at the rear of the wringer.

Like numerals in the various views designate like members. In Fig. 1 the wringer 30 is shown in position over the central partition of a pair of stationary wash tubs 2, the wringer being carried on a bracket 3 firmly bolted to it, and which bracket is in turn carried by two grooved rollers 4 35 loosely fitting and rolling on an angle iron track 5. The track 5 is part of a framework adapted to be secured to a wall 29 of a room, back of and above a pair of stationary tubs as shown.

40 The frame-work consists of a lower plank 6, and an upper plank 7, spacing and track supporting straps 8 and gear boxes 9.

The frame is secured in place against the wall 29 by the screws 10. The gear boxes 45 50 55 each contain a pair of bevel gears 11 and 12, as shown in dotted lines in Fig. 2. These gears all have square holes in the axis of their hubs as shown, the hole in the small gears being designated 13, and the hole in the large gear numbered 14. The small gears 11 are connected for power trans-

mission through their square holes by loosely fitting pieces of square shafting 15, as clearly shown in Fig. 3.

The small gear in the box at the extreme 60 right has an extended hub 30 on which an extra power pulley 16 is shown in Fig. 1.

The wringer has an extended shaft 17 from the lower roller 27 and is squared for a short distance and also slightly tapered, 65 as shown in Fig. 2. This wringer extension shaft can be inserted in the exposed square hole in any of the large gears in the gear boxes, at the pleasure of the operator, by simply supporting the lower end 70 of the wringer and rolling the bracket to a position over the desired gear box and then pushing against the lower part of the wringer, and if the gears 12 are revolving the square holes will soon coincide with the 75 squared end of the wringer shaft and engagement will be effected, as the wringer is free to move bodily toward and away from the gear box, it being free to swing from its point of suspension, the loosely fitting 80 rollers 4 on the track above.

The wringer is held in engagement by the lever hook 18 engaging a projection 31 on the gear box, and which lever when released by an upward push on its forward 85 end 19 permits of a spring releasing plunger 20 forcing the wringer away from the box and the wringer shaft out of the square socket, thereby instantly disengaging the wringer from the power, as so shown in 90 Fig. 2. The releasing plunger is actuated by a coiled spring 32 reacting against the wringer body.

The gear shafts 15 receive power from a reversing gear box, 21, properly positioned 95 on any power driven washing machine as indicated at 22, and should it be desired to reverse the wringer it may be done by reversal of its power source at that point, though for ordinary turning backwards to 100 release small articles wound around the wringer rolls, a small handwheel 23 is provided on the forward extension shaft 33 of the upper roll 28.

The gear shaft 15 is in several sections 105 fitting very loosely in, and having their ends within, the square holes in the pinions, the end connected to the power gear on the washing machine having the same construction, thus providing a semiflexible installation, making it impossible to cramp the pinion in their bearings by straining the 110

5 plank 6 in erecting it against an uneven wall, or through the run of gearing not being in perfect alignment or in alignment with the power box 21 on the washing machine.

10 Furthermore, when a washing machine, with which it is desired to use this rolling wringer and gearing, has its available gear power box distinctly out of line of the gear shaft 15, I provide universal joints on the shafts at the positions 24 and 25, as shown in Fig. 4 at 34 and 35, or their mechanical equivalent at any convenient point to make available a power connection to the machine.

15 To protect against danger and grease from the square power shaft I provide pipe covering 26 between gear boxes.

20 Instead of having the three separate power delivery sockets or gear boxes to afford three positions to the wringer, it will be readily seen that a single pair of gears could be made to slide along with the wringer on a long power shaft to accommodate any position of the wringer as shown 25 in horizontal cross section in Fig. 5 wherein the function of the parts are indicated by being similarly numbered to others already described in detail, but such an arrangement could not be so effectually sealed against 30 grease and danger as the other method shown in the drawings.

I claim:

1. In a device of the character described, 35 a gear box, a power delivery gear adapted to revolve therein, a clothes wringer adapted to be positioned in alignment with said gear, a shaft projecting from one of the wringer rolls adapted to engage said gear, automatic means for normally holding said 40 shaft away from engagement with said gear, and manually controlled means for holding said shaft in engagement with the gear.

2. In a device of the character described, 45 a series of horizontally spaced power delivery sockets with mechanical power transmitting devices connecting the sockets, a clothes wringer supported for horizontal movement and adapted to align with and engage separately any of the sockets, manually controlled means for engaging the wringer with the 50 sockets, and automatic means for disengaging the wringer upon releasing the manually controlled means.

3. A clothes wringer, means for supporting and guiding said wringer in horizontal adjustment, a power shaft extending along the path of adjustment, and means for effecting a power engagement from the shaft to the wringer at a plurality of definite spaced points only therealong and inoperative intermediate said points.

4. In a device of the character described, a horizontally disposed row of gear boxes, a

gear revolvably mounted in each box and connected one to the other by wobble shafts 65 for simultaneously driving all of the gears, a second gear revolvably mounted in each box each in mesh with one of the first mentioned gears and having a driving connection accessible from without the box, a 70 clothes wringer supported by a guide for movement along said row of gear boxes and having a power connection adapted to register with any of the driving connections of the second gears at positions of the wringer 75 along the guide adjacent the selected gear box.

5. In a device of the character described, a horizontally disposed row of spaced power delivery sockets, operative mechanical connection extending from one socket to the other for supplying power to all of the sockets, a clothes wringer supported by a guide for movement along the row of sockets and having a projecting roll shaft adapted 80 to register with any of the sockets at positions of the wringer along the guide respectively adjacent the sockets, and means for engaging the shaft with the selected 85 socket. 90

6. In a device of the character described, a horizontally disposed row of spaced power delivery elements, means for supplying power to the elements, a clothes wringer supported by a guide for movement along the row of spaced elements registering with any of the elements, and means adapted to effect a power engagement of the wringer 95 selectively with any of the elements upon registering of the wringer therewith. 100

7. In a device of the character described, a horizontally disposed row of spaced power delivery elements, a track horizontally arranged above and along the row of elements, a clothes wringer supported for movement along said track and adapted to pass the elements one after the other when moved therealong, and a power receiving device on the wringer adapted to align with any of the elements selectively and to be pushed 105 into engagement therewith. 110

8. In a device of the character described, a horizontally disposed row of spaced gear boxes, revolvable gears in said boxes, means for driving said gears, a track horizontally arranged above and along the row of gear boxes, a clothes wringer supported on the track for movement therealong, a power receiving shaft projecting from the wringer positioned to engage any one of the gears when the wringer is operatively adjacent thereto, and said wringer being rockable on the track whereby the shaft may be moved directly to and from a gear box to engage or disengage the gear with the shaft. 115 120

JULIEN A. BRIED.

Certificate of Correction.

It is hereby certified that Letters Patent No. 1,552,673, granted September 8, 1925, upon the application of Julien A. Bried, of Oakland, California, for an improvement in "Power Clothes Wringers," were erroneously issued to the inventor, said "Bried," as owner of the entire interest in the invention, whereas said Letters Patent should have been issued to the inventor, said *Bried*, and *Samuel L. Rogers, of San Francisco, California*, jointly, said Rogers being assignee of *one-half* interest in said invention, as shown by the records of assignments in this office; and that the said Letters Patent should be read with this correction therein that the same may conform to the record of the case in the Patent Office.

Signed and sealed this 10th day of November, A. D. 1925.

[SEAL.]

WM. A. KINNAN,
Acting Commissioner of Patents.
